UNITED STATES PATENT OFFICE

2,552,040

ELECTRON DISCHARGE DEVICE

Andrew V. Haeff, Washington, D. C., assignor to
Radio Corporation of America, a corporation of
Delaware

Application April 27, 1943, Serial No. 484,692,
which is a division of application Serial No.
375,029, January 18, 1941. Divided and this
application December 5, 1947, Serial No. 789,919

6 Claims. (Cl. 250—27.5)

1

My invention relates to electron discharge devices and associated circuits for use at ultra-high frequencies and particularly to the circuits in the form of resonant cavity circuits or resonators.

The present application is a division of my co-pending application Serial No. 484,692, filed April 27, 1943, now Patent No. 2,447,461, issued August 17, 1948, and assigned to the same assignee as the present application. Said co-pending application is a division of my earlier co-pending application Serial No. 375,029, filed January 18, 1941, now Patent No. 2,399,223, issued April 30, 1946, and assigned to the same assignee as the present application.

It has been demonstrated that tubes utilizing conventional grids for controlling current are well adapted for operation at ultra-high frequencies and retain their characteristic advantage of possessing high transconductance. However, one of the difficulties encountered in operating amplifying tubes at ultra-high frequencies is the presence of considerable loading in the input circuit which results in an excessive amount of power being required to drive the tube. This decreases the effective power gain of the tube when operated as an amplifier.

The fundamental causes of high input loading are: (1) ohmic and radiation resistance losses due to high circulating currents in electrodes and leads; (2) electron loading which results from the interaction of the electron stream with the circuit, including degenerative or regenerative effects caused by lead impedance.

In order to reduce ohmic resistance losses it is necessary to use internal leads and external conductors made of high conductivity material and having large peripheries. In addition, inter-electrode capacitances must be reduced as much as possible in order to minimize circulating currents. To reduce radiation losses a thoroughly shielded circuit of conventional design or closed type "cavity" resonators must be used.

The principal object of my invention is to provide an electron discharge device and associated circuit having means for substantially reducing or completely neutralizing electron loading when the device is used at ultra-high frequencies.

It is also an object of my invention to provide an electron discharge device having means for minimizing ohmic and radiation resistance losses when the device is used at ultra-high frequencies.

A still further object of my invention is to provide improved forms of resonant cavity tank circuits or resonators suitable for use with ultra-high frequency electron discharge devices and means for tuning the same.

2

The novel features which I believe to be characteristic of my invention are set forth with particularity in the appended claims, but the invention itself will best be understood by reference to the following description taken in connection with the accompanying drawing in which Figs. 1 and 2 are diagrammatic representations of electrodes and the movement of electrons between the electrodes; Figs. 3 and 4 are diagrammatic representations of conventional tubes and methods of operating the same; Figs. 5 and 6 are curves representing the relationship of the electron loading or conductance and the transit time of the electrons of the tubes in Figs. 3 and 4; Figs. 7 to 10 inclusive are diagrammatic representations of tubes and circuits made according to my invention for practicing my invention; Fig. 11 is a longitudinal section of an electron discharge device made according to my invention.

In order to understand better the effect of electron loading, the mechanism of interaction between the electron stream and the electrodes to which circuits may be connected will be reviewed. Consider a system of two electrodes 10 and 11 as shown in Fig. 1. Assume that electrons travel from the electrode 10, which may be a cathode, to the electrode 11, which may be an anode. During electron transit an image charge appears on the electrodes equal in magnitude to the total charge present at any moment within the inter-electrode space. The division of the image charge between the two electrodes depends, in general, upon the instantaneous distribution of charges moving within the inter-electrode space and upon the configuration of the electrodes. The current induced in an electrode due to motion of a charge is equal to the rate of time variation of the induced image charge on the electrode due to the moving charge. The total instantaneous current induced in the electrode by the electron stream will be found by summing the individual currents induced by all charges moving within the interelectrode space. If a voltage exists between electrodes 10 and 11, the displacement current due to the interelectrode capacitance must be also taken into account.

Consider now a three-electrode system formed, for example, by a cathode 10, a control grid 12 and the plate 11 of a triode. Two spaces have to be considered. The total current induced in the intermediate electrode 12 (Fig. 2) is contributed by moving charges in both spaces, 10—12 and 12—11, and the total current is equal to the vector sum of the two currents. The power generated or absorbed by the electron stream within the spaces 10—12 and 12—11 depends upon the re-

spective current, voltage and the phase angle between the current and voltage in each space. Thus, the power generated or absorbed within the spaces 10-12 and 12-11, will be:

$$W_{10-12} = i_{10-12} V_{10-12} \cos \phi_{10-12}$$

$$W_{12-11} = i_{12-11} V_{12-11} \cos \phi_{12-11}$$

In a more general case, such as a low- μ triode, when there may exist considerable penetration of the electric fields from space 12-11 into space 10-12, one must also consider direct-interaction between electrodes 11-10, so that a power

$$W_{10-11} = i_{10-11} V_{10-11} \cos \phi_{10-11}$$

also must be taken into account.

In order to reduce the electron loading the total power must be reduced to a minimum. This can be accomplished by choosing currents, voltages and their respective phases in such a way that the total power $W_{10-12} + W_{12-10} + W_{10-11}$ is a minimum.

In a conventional negative grid tetrode operated at low frequencies the input electrode loading will be negligibly small if the driving voltage is applied in a conventional manner between the grid and the cathode so that the voltage also appears between the control grid G and the screen S. (See Fig. 3.) The radio frequency electronic current passing in the G-S space is very nearly equal and opposite in phase to the current in the C-G space so that the total driving power is very nearly zero ($W = iV_{C-G} - iV_{G-S} \approx 0$). However, in a circuit shown in Fig. 4 where the driving voltage is applied between the grid and the cathode only, but does not appear between the grid and the screen, the loading will be very severe at low frequencies. This loading is due to the fact that even though a current, equal to C-G space current, flows in the G-S space, no voltage is present in this region and hence no negative power is developed in the G-S space to balance the power absorbed in the C-G space.

As the driving frequency is increased the circuit of Fig. 3 will exhibit electron loading which initially will increase with frequency. This loading is due to the fact that with increasing electron transit time with respect to a period of the driving frequency the amplitudes and phases of currents in the C-G and G-S spaces change in such a manner that the amounts of power absorbed and generated in the two spaces no longer balance each other. For the case of a high- μ control grid when the spacings and direct current voltages are such that the G-S electron transit time is negligible compared to C-G transit time an analysis shows that the electron loading or conductance will vary with transit time as shown in Fig. 5. Here the ordinates of the curve represent the ratio G/Gm_0 where G =conductance of the grid G due to electron motions and Gm_0 =transconductance of the grid G at very low or zero frequency, that is when the transit time of the electron is negligible in comparison to the time of one cycle of the frequency of the applied voltage. The abscissae represent the ratio τ/T , that is, the ratio of the transit time of the electron to the period of oscillation of the applied alternating voltage. The electron loading increases rapidly with transit time, reaches a maximum at the value of transit time τ equal to 0.85 of the oscillation period T and then, under ideal conditions, passes through zero and becomes negative. In the case of circuit shown in Fig. 4 the variation of electron loading with transit time will be as shown in Fig. 6. Starting

with its maximum value at low frequency the loading decreases with increasing frequency.

These curves indicate that for certain values of electron transit angle, that is, for certain values of the ratio of

$$\frac{\tau}{T} = \frac{\text{transit time}}{\text{period of oscillation}}$$

the loading will be small even for conventional input circuits. However, the values of frequency and operating voltages for these optimum conditions frequently lie outside the useful operating range of the tube. The tubes could be designed for this optimum condition but, in general, this may necessitate a compromise, so that high transconductance may be partly sacrificed. The present invention provides means for neutralizing electron loading for a wide range of frequencies and operating voltages without any sacrifice of the useful characteristics of the tube, such as high transconductance.

A general scheme is that in addition to the driving voltages applied between the cathode and grid, a voltage is developed between the control grid and the screen of such a magnitude and phase as to generate power in the grid-screen space and this power is fed back into the cathode-grid circuit, so that it will balance the power absorbed in the cathode-grid space.

A schematic diagram of such a circuit is represented in Fig. 7. An impedance Z_2 is introduced between the screen S and the grid G of such magnitude and phase angle that the current i_{G-S} will produce a voltage V_2 across this impedance. The power $W_2 = i_{G-S} V_2 \cos(\phi_{G-S} - \phi_{V_2})$ generated in the G-S space is then fed to the grid-cathode circuit Z_1 by means of a coupling circuit Z_0 . The impedances Z_1 and Z_2 usually take the form of tuned circuits and the coupling impedance Z_0 may be the inter-electrode capacitance or an auxiliary coupling element.

A modification of the circuit shown in Fig. 7 is represented schematically in Fig. 8, where the impedance Z_2 is shown introduced between the screen S and the cathode C rather than between the screen S and the control grid G. The coupling between the circuits Z_1 and Z_2 is provided by the control grid to screen capacitance or it can be supplemented by an auxiliary coupling circuit Z_0 . In Figures 7 and 8 conventional output circuits with output impedances (Z) connected between the anode and the screen are shown. However, other types of output circuits can be used, since the input loading neutralization scheme here proposed in no way depends upon the extraction of energy from the output circuit.

Fig. 9 shows schematically the input loading neutralization circuit in combination with an inductive type output circuit. Here the output circuit is connected between the two screening electrodes S_1 and S_2 . The suppressor and current collecting electrodes, represented respectively by S_3 and coll., are also shown. Fig. 10 represents schematically the input circuit arrangement of Fig. 8 in combination with the inductive-output circuit. In the above circuit diagrams only the essential radio frequency circuits are indicated. Blocking, grounding and by-passing condensers which are used for providing isolation of electrodes for direct current, so that different direct current voltages can be applied to different electrodes, are not shown.

One practical embodiment of my invention incorporated in a so-called "inductive output tube"

is shown in detail in Fig. 11. "Inductive output tubes" and their operation are described more fully in my United States Patent 2,237,878, issued April 8, 1941, and assigned to the Radio Corporation of America. Briefly, an inductive output tube comprises a cathode for supplying a beam of electrons and a collector for receiving the electrons. A modulating grid is placed adjacent the cathode for modulating the beam of electrons which passes to the collector. Surrounding the beam path is a resonant cavity circuit comprising a hollow member having a passageway extending therethrough through which the beam passes. The passageway is provided with a gap lying in a plane transverse to the beam path. As the modulated beam of electrons passes across this gap, energy is transferred from the beam to the resonant cavity circuit which provides the output circuit for the tube and which can be coupled to a radiator or to an amplifier.

In Fig. 11 is shown a longitudinal section of an electron discharge device made according to my invention in which all of the resonant cavity circuits are placed outside the evacuated envelope 70. The concave spherically curved cathode 71, which is indirectly heated is provided with heater leads 72 and 73, lead 73 serving also as the lead for the cathode. A control grid 74 is positioned closely adjacent the cathode and has the same configuration, the screen and accelerating electrodes 75 and 76 being supported from the glass envelope by means of leads 75' and 76'. The collector 77 is provided with the radiating fins 78 and the lead and support wire 79. A secondary electron suppressor 80 is positioned within the collector adjacent the mouth of the collector and acts to suppress secondary electrons generated within the collector. The inductive output or tank circuit comprises a pair of flat circular metal discs 82 and 83 connected together at the periphery by means of the ring-shaped member 84. The output gap is formed between the two electrodes 85 and 86 connected to and electrically supported by the disc-shaped side members of the tank circuit, side 82 being provided with an annular extension 87 into which the cylinder or collar 88 is slidably fitted to provide a tuning condenser for the tank circuit, the collar being provided with a radially extended lip 89 and adjusted by means of insulating rod 90 on the side of the tank circuit. The condenser cylinder is slidably supported on the electrode 86 by means of the insulating collar members 91 and 92. The leads 75' and 76' are connected to the extension 81 and the disc 83, respectively.

The cathode-grid concentric line circuit comprises the inner tubular member 93 which serves to shield the cathode leads, the outer tubular member 94 coaxial with and concentric with the inner tubular member 93, and the apertured shorting disc 95 electrically connecting the two tubular members. The cathode 71 is capacitively coupled to the inner tubular member 93 by means of the cup-shaped extension 96 electrically connected to the cathode lead 73 and insulatingly supported on the inner tubular member 93 by means of the insulating collar 97. The grid 74 is electrically connected to the outer tubular member by means of the spring contacts 98. The resonant cavity for the screen electrode-grid circuit is provided by means of the outer tubular member 99 coaxial with and surrounding member 94 and shorted by means of the apertured disc-shaped member 100. The open end of tubu-

lar member 99 is capacitively coupled to the extension 87 of disc 82. The cathode-control grid circuit is tuned by means of a tuning ring 101 slidably mounted between the tubular members 93 and 94 and provided with an adjusting rod 102. The screen electrode-control grid circuit is tuned by means of the tuning ring 103 provided with the adjusting rod 104 and slidably supported on tubular member 94 by means of the insulating ring-shaped members 105 and 106. To feed back energy from the screen grid-control grid circuit to the cathode-control grid circuit, I provide an L-shaped loop member 107 extending from the space between members 94 and 99, through apertures in members 100 and 94, into the interior of tubular member 94. Adjustment is provided by means of the rod 108. To couple the cathode-grid circuit to a driver, a loop 109 is provided extending through an aperture in the tubular member 94. The output from the output tank circuit is obtained by means of the loop 110 extending within the aperture in the member 84 of the tank circuit. To focus the electron beam through the tube, solenoids 111 and 112 are provided for producing a magnetic field in the direction of the tube axis.

The grid bias voltage is obtained from the voltage source 113 through a voltage divider 113', the cathode heating circuit being provided by means of a transformer 114 connected to a voltage source. The tank circuit is maintained at a highly positive potential with respect to the cathode by means of voltage source 115 which may be greater than voltage source 116 provided with the collector.

In operation the input voltage is applied through the loop 109 to the cathode grid tank circuit including tubular members 93 and 94. This causes the grid 74 to modulate the electron stream from the cathode 71. This modulated beam of electrons passes by the gap 94' in the screen-control grid circuit delivering energy to the resonant cavity circuit consisting of the cylinders 94 and 99 which energy is fed back to the cathode-control grid circuit by means of loop 107 in order to minimize the amount of driving power. The modulated stream then passes through the accelerating electrode 75, past the gap 86' to energize the output tank circuit 82, 83, 84, the decelerated electrons being absorbed by the collector 77 at a lower velocity. The output is obtained from the tank circuit by means of the loop 110 extending within the tank circuit.

It will thus be apparent that by means of the construction shown in Fig. 11 that losses due to the electron loading effects in the input circuit are reduced to a minimum by my invention. Ohmic and resistance losses due to high circulating current in electrodes and leads are reduced to a minimum due to the fact that concentric lines and resonant cavities used are of high conductivity material and large diameter and due to the effective by-passing of the radio frequency currents. Radiation losses are reduced to a minimum because of the shielded circuits. Thus, all three objects contemplated by my invention are practiced to provide a tube particularly suitable for use at ultra-high frequencies.

While I have indicated the preferred embodiments of my invention of which I am now aware and have also indicated only one specific application for which my invention may be employed, it will be apparent that my invention is by no means limited to the exact forms illustrated or the use indicated, but that many variations may

be made in the particular structure used and the purpose for which it is employed without departing from the scope of my invention as set forth in the appended claims.

What I claim as new is:

1. A resonant cavity tank circuit comprising a first tubular member and a second tubular member surrounding said first tubular member, said tubular members being electrically connected together to provide a coaxial line tank circuit and a tuning means for said coaxial line tank circuit including a conducting member slidably and insulatingly supported on the first tubular member and positioned between the inner first member and the second tubular member, and movable longitudinally of said tubular members for tuning the tank circuit.

2. A resonant cavity tank circuit comprising a first tubular member, a second tubular member surrounding said first tubular member, said tubular members being electrically connected together to provide a coaxial line tank circuit and tuning means for said coaxial line tank circuit including a conducting member within said second tubular member surrounding and slidably longitudinally of the first tubular member, said conducting member comprising an annular-shaped conducting member and a pair of oppositely disposed annular-shaped insulating members surrounding said inner tubular member and supporting said annular-shaped conducting member in spaced relationship with respect to said tubular members.

3. A coaxial line resonant cavity tank circuit including an outer tubular member and an inner tubular member, said tubular members being electrically connected together, and means for tuning said resonant cavity tank circuit including an annular-shaped member of conducting material, a pair of insulating collar-like members slidably mounted on the inner tubular member and provided with flanges lying parallel to the longitudinal axis of said tubular members and engaging said annular conducting member and supporting said annular conducting member in spaced relation to said tubular members.

4. A cavity resonator structure adapted for use with an electron discharge device having an envelope containing a cathode structure at one end for directing a beam of electrons along said envelope and another electrode toward which said electrons are directed, said cavity resonator structure including a first cavity resonator comprising inner and outer hollow tubular members coaxial with each other and having a member extending between said coaxial members at one end and providing an enclosed space between said coaxial members and a second cavity resonator at the opposite ends of said coaxial tubular members and comprising a pair of spaced plate-like members lying perpendicular to the longitudinal axis of said tubular members and closed at their pe-

ripheries and having registering apertures registering with the passage through the inner tubular member, said resonators being adapted to receive said electron discharge device within the inner tubular member to extend through said apertures.

5. A cavity resonator structure adapted for use with an electron discharge device having an elongated envelope containing a cathode structure at one end for directing a beam of electrons along said envelope and another electrode toward which said electrons are directed, said resonator structure including a first cavity resonator comprising inner and outer hollow tubular members coaxial with each other and having a conducting member extending between said coaxial members at one end and providing an enclosed space between said coaxial members and a second cavity resonator at the opposite ends of said coaxial tubular members and comprising a pair of spaced disc-like members closed at their peripheries and having apertures centrally thereof registering with the passage through the inner tubular member, said resonators being adapted to receive said electron discharge device within the inner tubular member to extend through said apertures, with the cathode end of said envelope within said tubular member.

6. A cavity resonator structure adapted for use with an electron discharge device having an envelope containing a cathode structure at one end for directing a beam of electrons along said envelope and another electrode toward which said electrons are directed, said cavity resonator structure including a coaxial line comprising inner and outer hollow tubular conductors coaxial with each other, and a cavity resonator at one end of said coaxial tubular members and comprising a pair of spaced plate-like members lying in planes transverse to the longitudinal axis of said tubular members and closed at their peripheries and having registering apertures registering with the passage through the inner tubular member, said coaxial line and said cavity resonator being adapted to receive said electron discharge device within the inner tubular member to extend through said apertures.
